Primary Examiner — Paula Allen Green(74) *Attorney, Agent, or Firm* — Adler Pollock & Sheehan P.C.; Daniel J. Holmander, Esq.(57) **CLAIM**

The ornamental design for a speaker, substantially as shown and described.

DESCRIPTION

FIG. 1 is a front perspective view of a speaker;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The elements depicted in broken lines in the various figures are included for environmental purposes only, and form no part of the claimed design.

1 Claim, 7 Drawing Sheets(56)
